BLOWOUT PREVENTER

John W. MacClatchie, Los Angeles, Calif., assignor to MacClatchie Manufacturing Company of California, Compton, Calif., a corporation of California

Application January 28, 1936, Serial No. 61,153

11 Claims. (Cl. 166—15)

This invention is a blowout preventer for wells, and has for an object to eliminate binding engagement of a closure means while it is being shifted to operative or inoperative position, and to tightly seat the closure means when it has been moved to operative position so as to provide an efficient seal.

It is a further object of the invention to shift the closure means to operative or inoperative position by oscillation of cooperating elements in a cooperating housing, with the cooperating elements having bearing fit in the housing for free oscillation, and being radially displaced when they reach operative position so as to then tightly seat against the housing.

It is a still further object of the invention to adapt the cooperating elements for engagement when they reach operative position, with said engagement at a surface and not at a mere line of contact.

It is a still further object of the invention to arrange the cooperating elements so that when oscillated to one operative position their engagement provides a closure throughout their entire surfaces of contact, and when reversely oscillated to another operative position their engagement provides a closure at their surfaces of contact having a restricted bore opening therethrough for snug reception of a well string.

It is a still further object of the invention to arrange the closure means so that when shifted to its operative position wherein a closure is formed throughout the entire surface of contact of its cooperating closure elements, subterranean pressure in the well will tend to tighten the radial seating of the closure elements against the housing, thereby effectively sealing the well; and when the closure means is shifted to its operative position wherein the surface of contact between its cooperating closure elements has a bore opening therethrough for passage of a well string, the weight of the well string will tend to tighten the radial seating of the closure elements against the housing, thereby effectively sealing the well around the well string.

It is a still further object of the invention to provide an operating means for the closure elements, which when the closure elements are in inoperative position is adapted to first swing the closure elements to either of their operative positions without the closure elements binding against the housing, and to then radially displace the closure elements when they have reached their operative position so as to maintain the closure elements tightly sealed against

the housing, and which when the closure elements are in either of their operative positions is adapted to first release the closure elements from their radial binding against the housing and to then swing the closure elements back to their inoperative position without binding against the housing during said reverse oscillation.

It is a still further object of the invention to provide a remote control for the operating means, and to preferably actuate the operating means by fluid pressure and/or manual means.

Further objects of the invention will be readily understood from the following description of the accompanying drawings, in which:

Fig. 1 is a front elevation of the invention.

Fig. 2 is a vertical section on the line 2—2 of Fig. 1.

Fig. 3 is a transverse section on the line 3—3 of Fig. 2.

Fig. 4 is a fragmentary view similar to Fig. 2, showing the closure means swung to one of its operative positions.

Fig. 5 is a transverse section on the line 5—5 of Fig. 4.

Fig. 6 is a view similar to Fig. 4 showing the closure means swung to its other operative position.

Fig. 7 is a transverse section on the line 7—7 of Fig. 6.

Fig. 8 is a vertical section on the line 8—8 of Fig. 4.

Fig. 9 is a diagram of the control valve.

The blowout preventer is preferably used in connection with a usual well structure which includes well casing 1 adapted to receive a well string such as drill pipe or production tubing, shown in the present instance as tubing 2 having coupling collars 3.

A housing is mounted on the casing 1 and has upper and lower openings 5—6 concentric with the bore of the casing. Transversely of the axis of the casing 1 the housing forms a cylinder 7 which is closed at its ends by detachable plates 8. A closure means is movable in the cylinder 7 to inoperative position clearing the prolongation of the aligned openings 5—6 as shown at Fig. 2, or is movable to operative position overlying one or the other of the openings 5—6 and tightly engaging the wall of cylinder 7 so as to close and seal the opening. The closure means is preferably adapted for shifting in one direction as shown at Fig. 4 so as to overlie and completely close the opening 5, or is adapted for shifting in the opposite direction as shown

at Fig. 6 so as to overlie the opening 6, in which position the closure means seals around the opening but has a restricted bore opening through the closure means concentric with the opening and adapted for passage of the well string 2 through said restricted opening.

As an instance of this arrangement the closure means may comprise cooperating plates 10-11, which are arcs of a cylinder, these closure plates being journaled in the cylinder 7 at opposite sides of the axis of the openings 5-6, with the outer peripheral bearing surfaces 12 of the arcuate closure plates concentric with the cylinder 7, and with the ends 13 of the arcuate closure plates preferably bearing against arcuate guides 14 on the end plates 8. The top and bottom surfaces of the arcuate closure plates are shown at 15 and 16 respectively, and are of appreciable area and extend radially of the cylinder 7 so that when the closure plates are swung to one or the other of their operative positions shown at Figs. 4 and 6, either the surfaces 15 or 16 abut throughout their entire areas and with said abutment at the axis of the openings 5-6. 25 The top surfaces 15 are flat surfaces throughout their entire area so that when they abut as shown at Fig. 4 the plates 10-11 completely close the opening 5 as shown at Fig. 5, and the bottom surfaces 16 are semi-cylindrically recessed medially of their length, and are flat surfaces beyond these medial recesses, so that when the surfaces 16 abut as shown at Fig. 6 the plates 10-11 completely close the opening 6 except for a restricted bore 17 which is defined by the cooperating medial recesses. The restricted bore 17 is concentric with the opening 6 and is of a diameter to snugly receive the well string 2, with one of the coupling collars 3 of the well string adapted to seat on the surfaces of the cooperating closure plates which surrounds the restricted bore 17.

When the cooperating plates 10-11 thus close either the opening 5 or 6 they seal around said opening, and when in the operative position shown at Fig. 6 they also seal around the well string which extends through the bore 17. For this purpose packing at the bearing surfaces 12 is adapted to engage the wall of cylinder 7, and packing is also provided at the abutment surfaces 15 and 16 and in the bore 17. The packing is preferably mounted in grooves in the arcuate plates 10-11, and may comprise strips of packing 20-20a extending lengthwise of the bearing surfaces 12 medially of their arcuate width, with packing strips 21-21a extending from the ends of the strips 20-20a and along the bearing surfaces 12 to the respective abutment surfaces 15-16. Packing strips 22-22a extend from the ends of strips 21-21a across the abutment surfaces 15-16, and the strips 22 and 22a are respectively connected by packing strips 23-23a which extend along the abutment surfaces 15-16. The packing strips 23a which extend along the abutment surfaces 16 also extend around the bore 17 as shown at 23b.

When the closure plates are in the operative position shown in Fig. 4, the packing strips 20-21 thus seal completely around the opening 5 as shown at Fig. 5, and the packing strips 22-23 seal the cooperating abutment surfaces 15. In similar manner when the closure plates are in the operative position shown at Fig. 6, the packing strips 20a-21a seal completely around the opening 6 and the packing strips 22a-23a seal the cooperating abutment surfaces 16, with the

packing strips 23b sealing completely around the well string 2.

The closure plates 10-11 are adapted for dependent swinging movement in the cylinder 7 to either their intermediate inoperative position shown at Fig. 2 or to one or the other of their operative positions shown at Figs. 4 and 6. For this purpose cranks 30 and 31 may be journaled in the cylinder 7 concentric with the axis thereof, with the shafts of the cranks preferably projecting outwardly beyond the respective end plates 8. As shown at Fig. 3 the throws of the cranks are of such dimensions as to clear the prolongation of the openings 5-6 when the closure plates 10-11 are in their intermediate inoperative position, and clear the well string 2 and its coupling collars 3 when the closure plates are swung to either of their operative positions shown at Figs. 4 and 6.

To permit convenient assembly of the parts 20 the throws of the cranks are offset from one another longitudinally of the cylinder 7 as shown at Fig. 3, so that at one end of the cranks the arm 30a of the crank 30 is inside the arm 31b of the crank 31, with the shaft 30c which projects from the crank arm 30a journaled in a hollow shaft 31d which projects from the crank arm 31b, while at the opposite end of the cranks the arm 30b of the crank 30 is outside the arm 31a of the crank 31, with the shaft 31c which projects from the crank arm 31a journaled in a hollow shaft 30d which projects from the crank arm 30b. The shafts 30d-31d are journaled in the end plates 8, and the shafts 30c-31c project outwardly beyond the shafts 31d-30d, but are of such restricted length that when during assembly and disassembly of the parts the cranks 30-31 are relatively longitudinally shifted until the arm 30a is alongside the arm 31a, the shafts 30c-31c will have been completely withdrawn from the hollow shafts 31d-30d, thereby permitting relative lateral displacement of the cranks.

In order to seal the housing 7 where the crank shafts project outwardly through the end plates 8, packing 33 is preferably provided in the bores of the hollow shafts 30d-31d so as to engage the shafts 31c-30c, and similar packing 36 is provided in the end plates 8 at the bearings for the hollow shafts 30d-31d. The packing 33 and 36 is preferably hydraulic packing operatively expanded by pressure in the housing 7, the pressure being preferably admitted to the packing 33 via ports 34 in the crank arms 30a-31a, with said ports communicating with annular channels 35 in said crank arms, and the pressure being admitted to the packing 36 via similar ports 37 and annular channels 38 in the crank arms 30b-31b.

The cranks 30-31 are adapted for dependent opposite oscillation whereby they may be selectively swung to any one of the various positions shown at Figs. 2, 4 and 6, and for this purpose driving connections which preferably have a common drive, are adapted to respectively engage the projecting crank shafts 30c-31d and 31c-30d. As an instance of this arrangement beveled gears 40 may be fixed on the projecting hollow shafts 30d-31d, and oppositely facing beveled gears 41 are fixed on the ends of shafts 30c-31c which project beyond the shafts 31d-30d. A bevel gear 42 meshes with each pair of oppositely facing gears 40-41, and the gears 42 are fixed on shafts 43 which may be journaled on the end plates 8 as shown at 44. Ro-

tation of the shafts 43 in opposite directions thus dependently swings the cranks 30-31 in opposite directions, and by reversing the direction of rotation of the shafts 43 the cranks may be 5 swung in either of reverse directions.

A common drive is preferably provided for the shafts 43 and may include segmental gears 45 fixed on the shafts 43 and meshing with gears 46 which are journaled on the housing 7 and 10 which in turn mesh with opposite sides of a rack 47, the rack being preferably guided on the housing 7 as shown at 48. The common drive may be power actuated and is preferably also adapted for manual actuation.

15 As an instance of a suitable power drive the rack 47 may be connected to a piston rod 50 which is in turn connected to a piston 51. The piston is adapted for reciprocation in a cylinder 52, and by a suitable valvular control A, preferably manually operated at a point remote from the blowout preventer, fluid pressure from a suitable source and which is supplied via a conduit 54, may be selectively admitted to either end of the cylinder 52 so as to selectively shift the rack 47 in either of reverse directions and thereby oppositely rotate the shafts 43 in either of reverse directions.

As an instance of manual actuation for the driving mechanism, one of the shafts 43 may be 20 extended by means of a flexible shaft 56 to a point remote from the blowout preventer, and may be rotated by a hand wheel 57 which preferably has a clutch engagement 58 with the shaft 56. The clutch is normally disengaged, and in 25 order to manually actuate the driving connection the hand wheel 57 is first axially shifted to engage the clutch 58 and is then selectively rotated in either of reverse directions so as to dependently swing the cranks 30-31 in either of reverse 30 directions.

40 Operating connections are provided between the cranks 30-31 and the closure plates 10-11. When the closure plates are in inoperative position as shown at Fig. 2 and during oscillation 45 of the closure plates to one or the other of their operative positions shown at Figs. 4 and 6, the operating connections permit running fit of the closure plates in the cylinder 7; and when the cranks have swung the closure plates to one or 50 the other of their operative positions, the operating connections provide for radially displacing the closure plates with relation to their normal axes of rotation, and which normal axes are 55 concentric in the illustrated embodiment of the invention, so as to seat the closure plates tightly against the wall of cylinder 7, at one or the other of the openings 5-6.

As an instance of this arrangement the inner 60 peripheral surfaces of the arcuate plates 10-11 form cam surfaces 60-61 extending from low points 62 midway of the arcs of said plates, toward the respective ends of said arcs, and the cranks 30-31 have projections 63 which are adapted to ride along these cam surfaces. The 65 arcuate plates 10-11 are yieldingly held against circumferential displacement in either direction relative to the cranks 30-31, as for example by springs 64-65 which are fixed to the plates 10-11 with their free ends respectively bearing 70 against the upper and lower sides of the arms of the cranks.

The projections 63 are preferably radially adjustable with relation to the cranks 30-31 as shown at 66, and are so adjusted that with the 75 cranks and the closure plates in the position

shown at Fig. 2, in which position the projections 63 engage the low points 62 and the parts are yieldingly held in this relative position by the springs 64-65, the projections 63 do not force the closure plates 10-11 tightly against the wall 5 of the cylinder 7, but permit free bearing fit of the closure plates in the cylinder. As the cranks are then swung toward one or the other of the positions shown at Figs. 4 and 6, either the springs 64 or 65 prevent relative circumferential movement between the cranks and the closure plates, thereby oscillating the closure plates with the cranks, with the projections 63 still engaging the low points 62 so that the bearing surfaces 12 10 continue to have free bearing fit in the cylinder 7. 15

When the closure plates have reached either of their operative positions with either their surfaces 15 or 16 abutting so as to arrest further movement of the closure plates, continued swinging movement of the cranks 30-31 causes either 20 the springs 64 or 65 to yield, so that the projections 63 then ride along either the cam surfaces 60 or 61 to the high points of the cams as shown at Figs. 4 and 6, thereby radially outwardly displacing the closure plates 10 and 11 so as to 25 tightly seat their bearing surfaces 12 against the concentric surface of the cylinder 7, and thereby tightly sealing around either the opening 5 or 6. This cam engagement maintains a tight seal as long as the parts remain in either of the operative 30 positions as shown at Figs. 4 and 6.

When the cranks 30-31 are then oscillated in the reverse direction for returning the closure plates to their inoperative position, the projections 63 first ride along either the cam surfaces 60 35 or 61 to the low points 62, thereby releasing the closure plates 10-11 from binding engagement against the wall of the cylinder 7. Reverse oscillation of the cranks being then continued, the springs 64-65 hold the closure plates and the 40 cranks against relative circumferential movement, so that the closure plates are swung with the cranks to inoperative position as shown at Fig. 2, during which movement the engagement of projections 63 with the low points 62 permits 45 free bearing fit of the closure plates with relation to the wall of the cylinder 7.

With the closure plates in inoperative position as shown at Fig. 2, the driving means is preferably power actuated to swing the closure plates 50 to one or the other of their operative positions, and when the closure plates are to be returned to inoperative position, pressure against the ends of the piston 51 may be equalized and the hand wheel 57 rotated to swing the closure plates back 55 to the position shown at Fig. 2.

To permit this method of operation the valvular control A may be arranged as diagrammatically shown at Fig. 9, the valvular control including a valve plug 70 rotatable in a valve casing 71 60 and a second valve plug 72 rotatable in a valve casing 73, with the plugs 70-72 fixed to a common shaft 74 for dependent rotation by a suitable hand lever 74a. The valve casing 71 has an intake port 75 connected to the pressure supply pipe 65 54, and has outlet ports 76-77 communicating via conduits 78-79 with the respective ends of the cylinder 52. The plug 70 has a bore 80 co-operating with the ports 75-76-77, and when the plug 70 is turned to the position shown at Fig. 70 9 it shuts off pressure from both ends of the cylinder 52, and when turned as respectively indicated by the arrows C and D the bore 80 admits pressure to the cylinder at its upper and lower 75 ends respectively.

The valve casing 73 has an exhaust port 81 and has intake ports 82-83 communicating via conduits 84-85 with the respective ends of the cylinder 52. The plug 72 is recessed so as to provide a passageway 85a cooperating with the ports 81-82-83. The plugs 70-72 being dependently rotated, when the plug 70 is turned to the position shown at Fig. 9 the plug 72 is turned so as to open both ends of the cylinder 52 to the exhaust 81, as shown at Fig. 9, and when the plug 70 is turned as indicated by arrows C and D, the plug 72 is turned as indicated by arrows C' and D'. Either the upper or lower end of the cylinder 52 is thus shut off from the exhaust 81, with the 15 opposite end of the cylinder still open to said exhaust, and it is the end of the cylinder to which pressure is being supplied from conduit 54, which is thus shut off to the exhaust.

When the blowout preventer has been assembled on the casing 1, the valve A is turned to the position shown at Fig. 9, exhausting both ends of the cylinder 52, and the clutch 58 is engaged and the hand wheel 57 is turned so as to swing the closure plates 10-11 to inoperative position as 25 shown at Fig. 2, thereby shifting the rack 47 so as to center the piston 51 in the cylinder 52. The clutch 58 is then disengaged. The parts remain in this position until a blowout occurs, with an unobstructed continuation of the bore of the 30 casing 1 extending across the cylinder 7 between the closure plates 10-11 and their cooperating cranks 30-31, as shown at Fig. 2.

When a blowout occurs, the valve A is turned to the position C-C' or D-D' depending upon 35 whether the opening 6 or 5 is to be closed, and which in turn depends upon whether or not there is a well string 2 in the casing 1. The piston 51 is thus actuated by pressure from the conduit 54 so that it is shifted to one end or the other of the 40 cylinder 52 for swinging the closure plates 10-11 to one or the other of their operative positions, with the opposite end of the cylinder 52 remaining open to the exhaust.

The blowout preventer then remains in operative 45 position for as long as desired, and when the closure plates 10-11 are to be again swung to inoperative position, the valve A is turned to the position shown at Fig. 9 and the piston 51 is again centered in the cylinder 52 by operating the 50 hand wheel 57.

The blowout preventer is thus adapted for movement of its closure means to either operative or inoperative position, with the closure means tightly seated and sealed when in operative 55 position. The closure means is adapted to close and seal the opening 5, with subterranean pressure from the well tending to upwardly radially displace the closure plates 10-11 so as to tighten their sealing engagement with the wall of the 60 cylinder 7; or the blowout preventer is adapted to close the opening 6 with a well string 2 extending through the bore 17, and with the weight of the well string exerted downwardly against the closure plates 10-11 as a result of a collar 3 65 of the well string resting upon said plates, thereby tending to downwardly radially displace the closure plates so as to tighten their sealing engagement with the wall of the cylinder 7 and 70 around the well string which extends through the bore 17. The arrangement is also such that either the surfaces 15 or 16 of the closure plates are adapted for abutment throughout the entire areas of said surfaces, with said surfaces of appreciable area, thereby insuring an effective seal.

I claim:

1. In combination, a housing having an opening communicating with a well bore, closure means for the opening comprising cooperating elements having flat abutment surfaces, and mountings for the cooperating elements adapting them for rotation for area contact of said abutment surfaces defining closed position of the closure means and also adapting them for radial displacement when in closed position for seating engagement with the housing responsive to subterranean pressure in the well bore. 5

2. In combination, a housing having an opening communicating with a well bore which is adapted to receive a well string, closure means comprising cooperating elements, and mountings for the cooperating elements adapting them for rotation for contact defining closed position of the closure means and also adapting them for radial displacement when in closed position for seating engagement with the housing, the cooperating elements having cooperating recesses defining a bore through the closure means when the cooperating elements are in said closed position, said bore being adapted to receive the well string 15 with a shoulder of the well string seated on the cooperating elements around said bore for radially displacing the cooperating elements by the weight of the well string exerted against the cooperating elements at said shoulder. 20

3. In combination, a housing having an opening therethrough communicating with a well bore which is adapted to receive a well string, closure means comprising cooperating elements, and mountings for the cooperating elements adapting 35 them for rotation in either of reverse directions for contact defining a closure for the opening and also adapting them for radial displacement when in closed position for seating engagement with the housing, the cooperating elements having cooperating recesses defining a bore through the closure means when said closure means is in one of its closed positions, said bore being adapted to receive the well string with a shoulder of the well string seated on the cooperating elements around 40 said bore for radially displacing the cooperating elements by the weight of the well string exerted against the cooperating elements at said shoulder, and the cooperating elements being adapted for radial displacement responsive to subterranean pressure in the well when the closure means is in the other of its closed positions. 45

4. In combination, a housing having an opening, closure means for the opening, a mounting for the closure means adapting it for running fit in the housing for movement to operative or inoperative position and also adapting the closure means for transverse displacement for seating engagement with the housing, and means for transversely displacing the closure means when in 50 operative position. 55

5. In combination, a housing having an opening, closure means for the opening, a mounting for the closure means adapting it for free running bearing fit in the housing for oscillation to operative or inoperative position and also adapting the closure means for radial displacement for seating engagement with the housing, and means for radially displacing the closure means when in 60 operative position. 65

6. In combination, a housing having an opening, closure means comprising cooperating elements rotatable for contact defining a closure for the opening, a mounting for the cooperating elements journaling them in the housing for free 70 75

running bearing fit and also adapting them for radial displacement for seating engagement with the housing, and means for radially displacing the cooperating elements when in closed position.

- 5 7. In combination, a housing having an opening therethrough communicating with a well bore which is adapted to receive a well string, closure means comprising cooperating elements, mountings for the cooperating elements adapting them 10 for rotation in either of reverse directions for contact defining a closure for the opening and also adapting them for radial displacement when in closed position for seating engagement with the housing, the cooperating elements defining a bore 15 through the closure means when said closure means is in one of its closed positions, said bore being adapted to receive the well string, and means for radially displacing the cooperating elements when in either of their closed positions.
- 20 8. In combination, a housing having an opening, closure means for the opening, a mounting for the closure means adapting it for free running fit in the housing for shifting to operative or inoperative position and also adapting it for transverse displacement for seating engagement with the housing, and operating means for shifting the closure to operative or inoperative position and for transversely displacing the closure means when in operative position.
- 25 9. In combination, a housing having an opening, closure means for the opening, a mounting for the closure means adapting it for free bearing fit in the housing for rotation to operative or inoperative position and also adapting it for radial

displacement for seating engagement with the housing, and operating means for rotating the closure means and for radially displacing the closure means when in operative position.

10. In combination, a housing having an opening, closure means comprising cooperating elements rotatable for contact defining a closure for the opening, a mounting for the cooperating elements adapting them for free bearing fit in the housing for rotation to operative or inoperative 10 position and also adapting them for radial displacement for seating engagement with the housing, and operating means for rotating the cooperating elements and radially displacing said cooperating elements when in closed position. 15

11. In combination, a housing having an opening therethrough communicating with a well bore which is adapted to receive a well string, closure means comprising cooperating elements, mountings for the cooperating elements adapting them 20 for rotation in either of reverse directions for contact defining a closure for the opening and also adapting them for radial displacement when in closed position for seating engagement with the housing, the cooperating elements defining a bore 25 through the closure means when said closure means is in one of its closed positions, said bore being adapted to receive the well string, and operating means for rotating the cooperating elements in either of said reverse directions and for radially displacing said cooperating elements 30 when in either of their closed positions.

JOHN W. MACCLATCHIE.
